[57] **ABSTRACT**

A character generator in which strokes are generated to form characters wherein each stroke is treated as a vector whose end points are stored digitally. The characters are formed from a variable number of strokes which are of varying periodicity such that a constant writing speed is obtained regardless of the number of strokes required per character; the time for writing a particular stroke is proportional to the stroke length. Two sets of digital to analog converters sum analog signal outputs in two channels such that digital control signals are loaded into the digital to analog converters alternately while X and Y axis beam steering and appropriate blanking and unblanking signals are employed for stroke writing.

CONSTANT WRITING RATE CHARACTER GENERATION AND DISPLAY SYSTEM

BACKGROUND OF THE INVENTION

This invention relates to a constant speed character generator in which characters are developed from a plurality of generated strokes which may be advantageously utilized in high data density display, such as are used in air traffic control systems.

In order to achieve high efficiency in a cathode ray tube display or stroke generator it is important that the writing speed be maintained substantially constant and that the blank beam lost time is minimized. These criteria are satisfied in a character generator in accordance with the principles of the present invention by selecting a writing time which is closely proportional to the written line length of the character to be written. The character is composed of a number of sectors of varying number and length in accordance with the character detail. The total time required to write a particular character is maintained the same regardless of the number of strokes or the length of the strokes required therefore by varying the segment periodicity, or the time required for the generation of the particular stroke or segment.

A problem of the prior art is a cumulative loss of accuracy which occurs when the end positions of segments are connected to form characters. The present invention uses a technique of combining positive and negative going ramps of different amplitudes in identical time periods to define the two end positions and all intermediate positions. The required amplitude is obtained by a multiplying digital to analog converter controlled by data in bit form obtained from read only memory. The advantage of using digital to analog converters to control the magnitude of the input ramp is that large quantities of digital words may be stored in extremely compact devices. Furthermore, this selection of characters is obtained directly from the digital numbers and no analog switching is required.

In systems of the prior art constant writing speed could only be obtained by the use of complex and costly brightness control circuitry since the writing time is not proportional to the written line length in such systems.

In another system of the prior art a beam current in a cathode ray tube display is generated proportional to a control signal defining the length of the vector to be generated, thus, the intensity of the beam current is controlled as a function of the beam velocity to afford a uniform display intensity irrespective of the length or of the velocity of the vector. However, in such systems complex intensity control circuitry is required and variably periodicity is not provided.

In other systems of the prior art the current required for stroke generation is proportional to the velocity of the stroke. While a character generator is described in the specific embodiment in which the characters are formed from a plurality of individual strokes and which is used in connection with an air traffic control system, it is to be understood that the techniques of the present invention could apply equally well to other systems requiring a constant speed character generator of high accuracy.

With constant writing speed it is only necessary to unblank the beam and no brightness compensation signals are required for the cathode ray tube.

SUMMARY OF THE INVENTION

A stroke generator for character generation is described in which a variable number of strokes is utilized in the generation of characters for visual display. The time duration of individual strokes is variable and proportional to the stroke length such that constant writing speed is maintained regardless of the number of strokes per character or the stroke length. This variable periodicity of the generated strokes is obtained in a combined digital and analog system in which segment periodicity data, segment end point data, timing and unblanking data are digitally generated and supplied to analog character generation circuitry. The rate supplying new digital words is slow relative to the rate at which the data is clocked into the analog circuitry.

The digital signals received by the analog circuitry produce coordinated X and Y channel waveforms and a blank/unblank signal to control the beam of a cathode ray tube to display cursorily written characters. The beam-on to beam-off time ratio is maximized by generating just the required number of segments for any particular character, and writing with substantially a constant speed. A wide range of segment length is obtainable such that a single segment is used for a straight line regardless of its length. Referencing is provided to either the center or a corner of the character.

Two triangular waveforms are generated to form a bipolar output which is summed to obtain a resultant waveform which is a ramp connecting the segment end points. A novel triangle generator is described in which a positive or a negative voltage is developed depending upon whether a positive or negative ramp analog output is required. The value of current from selected positive and negative current sources is determinative of the segment periodicity and is controlled digitally from a read only memory. The current sources are operative alternately, and during inoperative periods, data is received to change the triangle generator output to digital to analog multipliers to the value required for the generation of the next segment.

The triangle generator after amplification drives four digital to analog multipliers which operate in pairs with their multiplying factor being controlled by a digital input and changeable only when there is zero analog input. Thus, the digital word to the digital-to-analog multipliers is clocked in at alternate segment periods. For example, while one multiplier of a pair is generating an "odd" segment, the register of the other multiplier of the pair is receiving new digital data for the generation of the next segment, or the "even" segment; which is clocked in as the analog signal passes through zero.

BRIEF DESCRIPTION OF THE DRAWINGS

Further advantages of the invention will become apparent from the following specification taken in connection with the accompanying drawings wherein like reference characters identify parts of like functions throughout the different views thereof, and wherein in several of the views double lines indicate data flow.

FIG. 1 is a block diagram of an air traffic control system embodying the present invention.

FIG. 2 is a block diagram illustrative of the signal summation technique employed in the present invention.

FIG. 3 is a series of waveforms of the various signals generated throughout the disclosed summation means of FIG. 2.

FIG. 4 is a block diagram of the analog signal processing circuitry contained in a specific embodiment of the present invention.

FIG. 5 is a block diagram of the digital circuitry employed by the present invention.

FIG. 6 is a circuit diagram of a triangle generator in accordance with the present invention.

FIG. 7 is a circuit diagram of a phase inverter in accordance with the present invention.

FIG. 8 is a circuit diagram of a digital to analog multiplier in accordance with the principles of the present invention.

DESCRIPTION OF THE PREFERRED EMBODIMENT

Referring now to FIG. 1 a block diagram of an air traffic control system embodying the present invention is illustrated generally at 10. Data from air terminals at various locations such as weather conditions, flight pattern information, aircraft position and other data normally utilized by air controllers is inputted to a central computer 12 over a plurality of data channels A, B . . . N at which point the data is stored and the appropriate information is relayed to the local air terminals and air controller points such as 14 where a local buffer interface transfers the appropriate data to a local memory 16 which supplies positional, character and vector information to a character generator 18, a vector generator 20 and a positional generator 22 in accordance with the present invention. Vector generator 20 may be of conventional design as is the position generator 22 for controlling the deflection of the electron display beam of display 24 which may comprise a cathode ray tube. Other aircraft control points may be supplied in a similar fashion with a local buffer 26 receiving data in a parallel channel from the central computer 12 for transfer to a local memory 28 into the associated character generator 30, vector generator 32 and position generator 34 for the control of characters and vector information on a display 36.

Referring now to FIGS. 2 and 3, the principle of character generation employed by the present invention is illustrated. Two triangular waveforms, $V_R f(t)$ and $V_R(1-f(t))$ are multiplied by a gain function in digital to analog multipliers 50 and 52 respectively and summed in a summing network 54. Digital inputs containing stroke end point data are applied to the digital to analog multipliers 50 and 52 via data lines 56 and 58 respectively. Waveform $V_R f(t)$ is shown as A in FIGS. 2 and 3 and is one input for the X channel of the stroke generator. Waveform $V_R(1-f(t))$ is shown as B in FIGS. 2 and 3 and is the other input for the X channel of the stroke generator. The outputs of the digital to analog multipliers 50 and 52 are shown as A' and B'. The resultant R is a ramp connecting the end points which are determined by the multiplying factor.

As is apparent from FIG. 3, the amplitude of R, at the beginning and end of each segment is determined by the gain factors of the digital to analog multipliers 50 and 52 with the A and B channels alternately providing the end point values. The gain factors are controlled by five-bit words read from a digital memory to be

described with reference to FIG. 5. To obtain constant writing speed, the periodicity of the ramps must be varied, and the condition for constant writing speed is that $(\delta X^2 + \delta Y^2)/\delta T^2$ is a constant, where δT is the period of transition for δX and δY . The δX and δY are the deflection increments as scaled at the display screen. The period of transition is determined by a seven-bit word that is predetermined and stored in a digital memory. Of course, the number of bits determinative of the transition may be any amount desired. An unblanking bit is also stored in the digital memory in order to allow common formats for characters to be chosen which may be stored with the digital words. The digital word may effectively consist of five bits for X, five bits for Y, seven bits representative of time and three bits for unblanking for a total of 20 bits for each line segment. The three bits for unblanking allows choice of three unblanking sequences for a single writing pattern.

Referring now to FIG. 4 a block diagram of the analog portion of the character generator of the present invention is shown generally at 100. A size and offset voltage control is inputted to a character size voltage generating circuit 102 and a character offset voltage generating circuit 104 for developing V_R and V_o respectively. A triangle generator 106 generates triangular pulses of constant peak to peak amplitude with changing periodicity as is described with reference to FIG. 6. This series of triangular pulses is generated only when an unclamping signal inputted to the triangle generator via line 108 is low, otherwise no triangular output is generated. The clamping control is described with reference to FIG. 6. The amplitude of the generated triangular waveforms is determined by V_R with the slope of the positive going ramp determined by a seven-bit control signal received from a stroke segment memory via line 110 at digital to analog converter 112 which is coupled to a positive constant current source in the triangle generator while the slope of the negative going ramp is likewise controlled by a seven-bit control signal inputted via line 116 to a digital to analog converter 114 which is coupled to a negative constant current source in the triangle generator control signal 116.

A phase inverter 500 develops two phases of the triangular pulses as is described with reference to FIG. 7 and is capable of driving four digital to analog multipliers 120, 122, 124 and 126 of the type described with respect to FIG. 8. Digital to analog multipliers 120 through 126 each require five data bits to control the signal attenuation in a simple ladder network. The outputs of each pair of multipliers are summed at the inputs to line amplifiers 128 and 130. The outputs of line amplifiers 128 and 130 are the drive signals supplied to the X and Y axes respectively of the character display. The offset voltage V_o developed in offset generator 104 proportional to the size of the character and to the character size voltage V_R is also added to the line amplifiers 128 and 130.

A comparator in the triangle generator 400 produces a square wave which is negative during the period of positive going ramps and zero during the period of negative going ramps. This waveform is used to control gates for selecting the two phase blank/unblank signals obtained from the digital memory described with

reference to FIG. 5 for developing a fast switching speed of an unblanking signal output so that a slow change of digital signal from the memory can be tolerated. Clocking signals are derived from this squarewave in a conventional manner in a clock generator 132 which generates the odd clock pulses from the falling edge of the squarewave and the even clock pulses from the rising edge of the squarewave which are coupled to the D/A multipliers to the digital timing and control logic. These clock pulses cause the digital signals X and Y to be loaded into the five bit D/A multipliers 120 through 126 and are also used to activate the digital logic and memories.

The unblanking signal is selected at unblanking gates at amplifier 134 from a digital control signal from the digital timing and control logic and is amplified in the unblanking line amplifier 134. Dot unblanking is obtained from a monoshot circuit in the timing and control logic fed to the unblank gates.

The digital to analog multipliers 120 through 126 operate in pairs and are fed from the two phase outputs from the phase inverter 500. It will be observed that the multiplying factor controlled by the digital input to the digital to analog multipliers is only changed when its analog input is at zero, in other words, the multipliers have the digital input changed at the commencement of alternate segment periods, hence the terminology odd and even X and Y inputs to the D/A multipliers. Thus, when a five-bit signal is being clocked through a D/A multiplier after translation in signal translator 136, the other five-bit signal is being inputted to the other D/A multiplier for the same axis. The outputs of each pair of multipliers are summed in a resistance network and amplified to drive a 75-ohm unbalanced line.

Referring now to FIG. 5, the digital portion of the character generator is illustrated generally at 200. Timing and control logic in the digital circuitry generates suitable clock pulses for unloading a read-only segment memory in which the various stroke data is stored into the digital to analog converters in a timing sequence. Additionally, the timing and control logic serves to count the number of segment words for comparison with the number of words allocated for any particular character and is automatically reset when that number has been reached. When reset, new characters may be generated upon receipt of load and start signals by the control logic.

Data in the form of a six bit character code plus parity enters the system through the input logic shown generally at 202 which includes conventional shift registers 204 and the character address and control for a segment memory from which various control signals are derived as will be explained. In addition to the character code, size and offset control signals are received by a character code register 204, which are inverted by inverters 206 and 208 with the inverted signals being supplied to the analog size and offset circuitry described with reference to FIG. 4.

A parity bit is received in a conventional manner at a parity checking circuit 210 of conventional design. If parity is correct, the six bit character code and the size and offset signals, which are treated as data, are loaded into the character code register 204 in accordance with loading timing on line 212 from the timing and control logic. If parity is incorrect, the character code register

is reset to all zeros. Even and odd parity is imparted to the timing and control logic via lines 214 and 216 respectively, with the appropriate clearing signal being received via line 218 from the timing and control logic 220 at the character code register.

The character code is imputted to a read only starting address and control memory 222 via line 224 if parity is correct. Memory 222 is formed of integrated circuit logic modules of conventional design, and may be considered to be a code translator that permits the association of any starting address for the stroke segment memory with any six-bit character code. Thus, where the input character code is standard ASCII, memory 222 provides an address to the initial word in the segment memory, data specifying the number of segment words in the selected character, the location of the desired "two bit" (blanking) within the segment word, and data to distinguish between normal cursively written characters, a dot, and unused character codes.

Memory 222 is continuously accessed by the character code register 204 which supplies an enabling signal in addition to the character code. The memory portion of address and control circuitry 222 effectively comprises four 256-bit memory chips of 64 words, each of 16-bit length. A common format occurs when the same portions of the segment memory are used for the generation of different characters, for example, the vertical line present in an E, an F, and an L.

The output portion of the starting address and control memory comprises four four-bit MSI general purpose registers which may be loaded simultaneously with one word from the memory for each character to be accessed.

The segment memory 230 is a read only memory that contains all the data necessary to display the complete compliment of cursively written characters as well as a parity error symbol. The segment memory is divided into six blocks of 32 words each giving a total capacity of 192 words, with each word defining two 20-bit segments. The number of words per character format may vary, for example, from one to eight with the present coding but may be as large as 16. While theoretically a format could be placed anywhere within the memory, in actual practice the format location is limited to a single 16 word section so that only the four least significant bits of the address received on line 232 from the segment memory address register 234 are required to change during the display of a single character.

While the present design provides 41 formats including the parity error symbol it is to be understood that the memory may be expanded as desired in accordance with conventional integrated circuit techniques merely by adding additional memory circuit modules. For the display of a given character the starting address and control memory 222 supplies the segment memory address register 234 with an eight-bit starting address. The register 234 is a down-counter which then proceeds to count down sequentially until it is commanded to clear to all zeroes by the timing and control logic 220 via the clear segment memory address register line 236. Since there is a logic inversion in each of the 6 segment memory modules between the output of the counter 234 and the five-bit address inputs on line 232 to the memory chips, the segment memory chips actually receive an ascending address change while the final reset address consists of all ones.

The three most significant bits of the complete address are decoded in an address decoder 238 and inputted via line 240 to enable one of the six blocks of the segment memory. The reset word is located at the final address of the first block of the segment memory and under normal operation the segment memory will remain at this address until another written symbol is processed.

The segment memory 230, as previously described, contains 192 forty-bit words with the 40 bits in each word defining two successive 20-bit segments which may be considered 20-bit memory half words, i.e., one segment, each of which 20-bit half words comprises five bits to specify the horizontal or X end point of the segment, five bits to specify the vertical or Y end point of the segment, seven bits to specify a time number denoting the time duration of the segment and three bits, one for each of three possible characters within a format to specify whether the segment is blanked (a logical one) or unblanked (a logical zero) with the latter three bits being the blanking bits, or Z bits.

Both halves of the memory output word are loaded into the segment data memory registers at the same time. The segments however are processed sequentially through the rest of the circuitry with the first segment being the "odd" segment and the second segment being the "even" segment. The format may contain an odd or an even number of segments, if desired, while the second half of the last memory word is the same as the reset word. Z-bit, or blanking location information stored in the starting address and control memory 222 is loaded into the operation control register 242 in response to a loading signal on line 244 from the timing and control logic. This blanking or Z-bit control is inputted on line 246 to the Z-bit selection circuit 248 which is an MSI logical unit that performs a dual selection of a pair (odd and even) of Z-bits from the six Z-bits in the segment memory output supplied to the Z-bit selector 248 on data line 250. The control signal on line 246 comprises two bits which have the same value for all the words in any character format. The outputs of the Z-bit selection logical unit 248 are connected to segment data registers 262 and 264 of the output registers shown generally at 260 as will be explained. Timing signals are received by the word count register 266 from the control logic 220 on line 268 and each zero count is received by the timing logic on line 270. The timing signals necessary for dot generation are received by the operation control register 242 via line 272 and dot command signals are inputted to the timing and control from the operation control register 242 via lines 274 and 276.

The output registers 260 or the segment data registers, consist of 11 four-bit MSI shift registers. Five of these registers shown representatively as 280 are loaded in parallel with ten odd and ten even bits of X and Y end point data, five bits for X, and five bits for Y, with the odd segment bits alternating with the even segment bits. Data lines 282 and 284 from the segment memory couple ten-bit outputs which are alternate physical locations of the stroke end point data to registers 280 and are connected directly to the analog circuitry as described with reference to FIG. 4 via lines 286 and 288 where they are received at the appropriate time by either of two odd or even high speed registers. The outputs of registers 280 will contain the odd seg-

ment data immediately after the segment data registers have been loaded from the segment memory output word. At the next step in the operating sequence registers 280 will receive a shift clock pulse from the timing and control logic 220 via line 290 which causes the even segment data to appear on the ten output lines. From then on data lines 286 and 288 to the analog circuitry will alternate with odd and even segments until a reset from the segment memory is loaded in response to a clock signal from the timing and controlling logic via line 292. Lines 286 and 288 which represent the segment end points will then remain at a logical zero until the next character is processed. Since there is no master clear it is necessary to process at least one character after power turn on to arrive at the above logical zero condition.

Six MSI registers illustratively shown as registers 262, 264, and 294 each of which comprises two registers, are used to process the time periods and blanking data received via lines 296 and 250 respectively from the segment memory. Since the analog circuitry requires both odd and even stroke segments at the same time so as to enable it to switch rapidly from one segment to the next these registers 262, 264, and 294 operate differently than the X and Y end point shift registers 280. Registers 262 and 264 receive the eight bits (seven for time and one for blanking) corresponding to the odd segment eight bits corresponding to the even segment. The eight outputs from registers 264 which contains the odd segment data are connected directly to the analog circuitry via line 298. The eight outputs from registers 262 and 294 containing the even segment time and blanking data are coupled to the analog circuitry via line 300.

The even Z bit is inverted by inverter 302 before it is loaded into register 294. The first set of two registers, 262 for the even segment data is labeled A registers while the second set 294 is labeled B registers. The Z-bit output from the B registers is connected via an inverting gate (not shown) in the timing and control logic 220 to the analog circuitry while the other seven bits of the B register are connected directly to the analog circuitry. The even segment data lines to the analog circuitry are changed at alternate intervals from the odd segment data lines to the analog circuitry, however, both remain steady for two segment periods. At the end of the display for one symbol, the segment time period lines 298 and 300 for the odd segment period and even segment periods respectively will remain at logical zero while the blanking lines 304 for odd blanking and 188 for even blanking will remain at logical one. This logical one condition of the blanking lines in the case of the odd segment data results from the reset word from segment memory 230 while in the case of the even segment data the contents of the even B registers 294 are either that of the last memory word to be used in the character format when the total number of segments in the character is odd or that of the reset order when the total number of segments is even.

The timing and control logic 220 of the digital module provides all the clock signals and control levels required to implement the operations previously prescribed. This logic is the source of all the timing pulses required by the digital module which together with the odd clock and the even clock input lines from the

analog circuitry determine the order and time duration of the various operations required. In addition this logic unclamps and clamps the analog circuits, controls unblanking and provides various indications on the data console. The timing and control logic comprises conventional MSI logic modules. Clamp signals are applied to the analog circuitry via line 306 with dot blanking on line 308 which the odd and even clocks are received on lines 310 and 312 respectively. Various signals from the central computer are also received by the timing and control logic, such as enabling signals for data loading, and a central clock if desired on line 314, 316 and 318. An "end of character" signal is coupled on line 320 to the analog circuit.

Referring now to FIG. 6 the triangle generator is shown generally at 400. The triangular waveform generator 400 and the phase inverter 500 generate two phases of triangular pulses of constant peak amplitude but with changing periodicity. In the triangular waveform generator, a capacitor 402 is charged from either a positive or negative constant current source 404 or 406 respectively. The choice of source depends upon whether a positive or negative slope is required. A differential circuit in a comparator 408 alternately compares the voltage across capacitor 402 with zero volts and with the peak positive value V_R . This comparator 408 switches the constant current sources 404 and 406 such that when the voltage across capacitor 402 starts at zero the positive constant current source 404 is operative and the capacitor is charged until the comparator detects the value as being equal to V_R , at which point the positive current source 404 is then switched off and the negative current source 406 is switched on. Capacitor 402 is then discharged to zero and the whole cycle recommences.

Every time the comparator executes a complete cycle the segment word binary counter 266 is incremented by one count by a pulse generated by comparator 408 on line 410. The value of the current from the constant current sources 404 and 406 determines the period of time required for the voltage across capacitor 402 to vary between zero and V_R and is set by the seven-bit digital to analog converters and controlled via lines 298 and 300 by the even segment period and the odd segment period data from registers 300 and 298 respectively of the output registers of the digital circuitry. Since only one constant current source is operative at a time, during the inoperative periods it is possible to change the input to the seven-bit digital to analog converters to the value required for the next segment. The alternate inputs zero and V_R supplied to the comparator 408 are switched by a switching transistor 412. The voltage across the charging capacitor 402 is large compared with either V_R or zero. Thus, if compared with zero this voltage must be negative and if compared with V_R it must be positive. The transistor pairs 414 and 416 and 418 and 420 are differentially connected to form the comparator while transistor 422 acts as the positive current source and transistor 424 as a negative current source.

The peak positive voltage V_R is amplified by an emitter follower transistor 326 prior to comparison in comparator 409. Signal translation from the capacitor 402 to the positive current source 404 is provided by transistors 428 and 430. Transistor 432 switches off

while transistor 428 is on and transistor 428 switches off while transistor 430 is on in order that current loading from the positive and negative current sources 404 and 406 respectively to the comparator is kept approximately constant. The voltage across the capacitor 402 is amplified and phase inverted to provide the two phases required by the D/A multipliers as described with reference to FIG. 4. The triangle waveform generator supplies both the X and Y D/A multipliers 120 through 126 and the triangle waveform is phase inverted and reference to V_R to minimize transients when V_R is changed by varying the character size with the voltage V_R added to the supply voltage B+.

A clamp circuit indicated generally at 440 arrests the action of the triangular waveform generator on completion of a character which holds the voltage across capacitor 402 at zero under the command of control signals from the timing and control logic 220 received at 442. Diodes 444 and 446 act as restraining diodes for the clamp circuit, the output of which is of course applied to the capacitor 402. Transistors 448 and 450 form a differential amplifier, the output of which is coupled through emitter follower 452 to clamp the emitter voltage of transistor 454. Five-volt outputs are provided at the collectors of transistors 454 and 456 respectively, a supply voltage is provided at 458, and a potentiometer (not shown) provide a clamp level control at 460. Transistors 462 and 464 provide signal translation for the reference outputs to the positive Y-bit D/A converter at 466, 468 and 470 while reference output to the negative seven-bit D/A converter are provided by a connection to the emitter of transistors 424 and 432 and taps across a zener diode 472 at 474, 476 and 478 respectively. Transistor 480 and zener diode 482 provide biasing for the comparator 408. A negative 11.4 volts is supplied at 484.

Referring now to FIG. 7 the phase inverter is shown generally at 500. The peak signal amplitude or dc size control V_R which is a function of time is a unipolar signal inputted to the base of transistor 502 on line 504. A supply voltage which may effectively be 24 volts is applied through resistor 506 by an emitter follower circuit 508 through the collector of transistor 502 while the negative supply voltage is applied through resistor 510 to the emitter of transistor 502 thereby producing a bipolar output on lines 512 and 514 with $-V_{RF}(t) + V_b$ on line 512 and $+V_{RF}(t) + V_b$ on line 514 with V_b being the dc offset voltage. Capacitors 516 and 518 allow dc isolation to permit the triangular waveforms to be dc restored to new reference leads, V_R and zero. Diode 520 dc restores to V_R which is present on line 522 from the size control while diode 524 which is grounded at 526 and emitter follower 528 dc restore to ground. Thus two bipolar signals with approximately the same delay are inputted on lines 412 and 414 respectively to emitter followers 528 and 530 respectively to provide an even segment triangle voltage output on line 532 to the even D/A converters and an odd segment triangle voltage output on line 534 to the odd D/A converters.

Referring now to FIG. 8 a portion of a typical digital to analog multiplier of the present invention capable of accepting a single bit of data is illustrated generally at 600. The digital to analog multipliers operate in pairs as described with reference to FIG. 4 and are fed from the two phase outputs on lines 532 and 534 from the phase

inverter 500. The multiplying factor of the D/A multiplier is controlled by a digital input and is only changed when its analog input is at zero. In other words, the multipliers have the digital input changed at the beginning of alternate segment periods. The outputs of each pair of multipliers are summed in a resistance ladder network 630 and amplified to drive a 75-ohm unbalanced line. FIG. 8 is illustrative of the technique used to obtain rapid switching of the signal into the ladder while maintaining a relatively constant load on the source.

The waveform $V_{rf}(t)$ is inputted via line 602 to the base of transistor 604, the emitter of which is biased by resistors 606 and 608 and diodes 610 and 612. A single bit of X or Y end point data, is inputted on line 614 to a register section 616 along with a clock signal from the analog clock generator. This bit of data is coupled to a linear transistor pair of switches 618 and 620, which maintains constant input loading. As long as transistor 620 is clamped data will not be inputted to the ladder network 630; however, upon receipt of an unclamping signal, data is passed through to the ladder network and out to respective line amplifiers to form the deflection voltages.

Resistor 622 provides suitable biasing and diodes 624, 626, and 628 provide clamping for the transistors 618 and 620.

In the character generator described, X, Y, blanking, and period data are all digitally stored; however, this data could of course first be received on a communication line before local storage.

While particular embodiments of the invention have been shown and described, various modifications thereof will be apparent to those skilled in the art and therefore it is not intended that the invention be limited to the disclosed embodiments or to details thereof and departures may be made therefrom within the spirit and scope of the invention as defined in the appended claims.

What is claimed is:

1. A character generation system comprising:
means for generating a ramp function signal, said generation means providing a positive ramp function and a negative ramp function, said generation means being responsive to digital control signals of a storage means for controlling the temporal duration of each of said ramp signals such that each of said durations is predetermined in accordance with said digital control signals;
means for storing said digital control signals, said storage means being responsive to a computer supplied address for selecting a set of such digital control signals corresponding to a selected character which is to be generated;
first means for multiplying a ramp signal generated

by said ramp generation means by one of said digital control signals of said storage means for scaling said ramp signal;

means for complementing a ramp signal provided by said ramp generation means;

second means, coupled to said complementing means, for multiplying said complemented ramp signal by a second one of said digital control signals of said storage means for scaling said complemented ramp signal;

means for combining said scaled ramp signals of said first and said second multiplying means to provide the instantaneous value of a coordinate of a segment of said selected character;

means coupled to said combining means and responsive to said coordinate for displaying said character; and

said ramp generation means signaling said storage means to update the values of respective ones of said control signals to said first and said second multiplying means when each of said scaled ramp signals of respectively said first and said second multiplying means has a zero value, successive ones of said coordinates thereby being provided such that one coordinate is initiated immediately upon termination of a preceding coordinate.

2. The system according to claim 1 wherein said ramp generation means comprises a capacitor and a pair of current source means for charging and discharging said capacitor, each of said current source means providing for a continuously variable duration of said ramp signals in response to said control signals of said storage means.

3. The system according to claim 2 wherein said ramp generation means comprises comparator means for comparing the magnitude of said ramp signal to a reference signal, said comparator means terminating such ramp signal when said value of said ramp signal equals the value of said reference signal, and means for varying said reference signal in response to one of said control signals of said storage means to provide a continuously variable maximum amplitude to said ramp signals.

4. The system according to claim 2 further comprising means for computing air traffic control data, said computing means processing said data to provide a format for said data wherein said data appears in two portions, one of said portions being suitable to be applied as a control signal to said first multiplying means and said second portion being suitable to be applied as said digital control signal to said second multiplying means.

5. The system according to claim 2 further comprising means responsive to said control signal of said reference and coupled to said combining means for offsetting the center of a displayed character.
